UNITED STATES PATENT OFFICE.

BRADFORD H. DIVINE, OF UTICA, NEW YORK.

MACHINE FOR CLEANING AND POLISHING TIN.

No. 888,088.

Specification of Letters Patent. Patented March 24, 1908.

Application filed June 10, 1907. Serial No. 378,072.

To all whom it may concern:

Be it known that I, BRADFORD H. DIVINE, of Utica, in the county of Oneida and State of New York, have invented certain new and useful Improvements in Machines for Cleaning and Polishing Tin; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of my invention is to provide a machine for cleaning and polishing tin in the final stages of manufacture which is simple in construction, efficient in operation and as to which the cost of maintenance is reasonable.

A particular feature of the machine is the means provided for cleaning the rolls continuously during the regular operation of the machine whereby the rolls are kept always in the most efficient condition, and the wear and tear on the rolls minimized.

In the process of manufacturing tin as the tin comes from the tinning or coating bath, it is ordinarily passed through a flux of palm oil on the tinning bath, which besmears the surface of the tin. For the purpose of removing this palm oil the tin is subjected to a treatment of bran and lime, or sawdust and lime, and after being subjected to this treatment the tin is adapted to be operated upon by my present machine to remove the residue of the palm oil, the lime and bran or sawdust and to polish the surface of the tin so as to make it a desirable commodity.

Figure 1 shows a vertical section of a machine embodying the features of my invention. Fig. 2 is an end view of the same with some of the branching parts broken off. Fig. 3 is a partial side elevation. Fig. 4 is an enlarged cross sectional detail of the roll and roll cleaning devices. Fig. 5 is an enlarged plan sectional detail of the same.

Referring to the reference letters and figures in a more particular description, 1 and 2 indicate the upper pair of polishing rolls, and 3 and 4 the lower pair of polishing rolls, all mounted for rotation in the upright end frames 5 and adapted to be driven in the direction indicated by the arrows in Fig. 1. A pair of feeding rolls for the upper pair of polishing rolls are indicated by 6 and 7 while a pair of feed rolls for the lower pair of polishing rolls are indicated by 8 and 9. These

pairs of feeding rolls are adapted to be rotated in the directions indicated by the arrows in Fig. 1. Both the polishing rolls and the feeding rolls are preferably what are known as cloth rolls made of pile layers of cloth in the main, the feeding rolls preferably being quite hard and firm while the polishing rolls are comparatively soft. For the purpose of driving the polishing rolls the rolls 1, 2, 3 and 4 are provided on the outer ends of the shafts respectively with band pulleys 1^a, 2^a, 3^a and 4^a around which is woven a driving belt 10, which belt also passes around idle pulleys 11 and 12 to obtain correct directions and provide for maintaining tension. The feed rolls 6, 7, 8 and 9 are provided on the outer ends of their respective shafts with sprocket wheels 6^a, 7^a, 8^a and 9^a, around which is entwined, as shown in Fig. 2, the sprocket chain 13 which chain passes also around the idle wheel 14 and engages with a sprocket wheel at 15 located back of the pulley 11 and driven thereby.

It will be noted that the arrangement is such that the feed rolls are driven at a reduced speed from that at which the polishing rolls are driven. In front of the feed rolls 6 and 7 there is provided a chute 16, which facilitates the introduction of the sheets of tin between the said feed rolls. On the opposite side of the machine is a chute 17, which receives the sheet of tin and delivers it to the feed rolls 8 and 9. 18 is a chute which receives the sheet after being passed through the lower sets of rolls and delivers it on to a carrier 19. In connection with the polishing roll 1 there is provided a pipe 20 adapted to receive compressed air from a suitable source of supply, and having a slot or set of small openings adapted to direct a blast of air tangentially on the surface of the roll 1. A slotted scroll-shaped tube 21 is also provided, the outstanding edge of which is adapted to come in close contact with or touch lightly the periphery of the roll 1 adjacent to the point that receives the blast from the openings of the pipe 20. A suction may be applied at one end of the pipe 21. These two pipes 21 and 20 are mounted in swinging hanger 22 adjacent to the end frames of the machine, whereby they can be adjusted toward or from the roll 1, so as to lightly engage therewith and adjusted to the diameter of the roll as it may gradually wear away. For the purpose of adjusting there is provided a screw 23 engaging with the

arm 22 and mounted in a fixed nut on the frame. In connection with the polishing roll 2 is provided a similar blast pipe 24, dust and dirt removing pipe 25, hanger 26, and 5 adjusting screw 27. In connection with the roll 3 there is provided the blast pipe 28, the dust collecting and removing pipe 29, hanger 30 and adjusting screw 31. In connection 10 with the roll 4 is provided the blast pipe 32, the collecting pipe 33, the hanger 34 and adjusting screw 35. All these devices are 15 similar to the one used in connection with roll 1, but somewhat differently mounted.

The provision for connecting the ends of 15 the blast tubes 20 and suction tube 21 is shown in Fig. 5 in connection with the pipes 32 and 33, and may consist of a section of flexible hose 36 and 37 in each instance. For preliminarily removing such loose dirt 20 as may be on the upper surface of the sheet of tin there may be provided at the delivery end of the sheet 16 a blast pipe 40, and a scroll collecting and dirt removing pipe 41, similar to those used in connection with the 25 rolls but these need not necessarily be mounted for adjustment. The feed rolls 8 and 9 are provided with similar blast pipes and dust collecting and removing pipes to those employed in connection with the polishing 30 rolls and mounted in hangers and provided with adjusting screws, all in a substantially similar manner. It is also apparent that the feed rolls 6 and 7 may be similarly provided with cleaning appliances if desired. The 35 feeding rolls will be adjusted to bear quite heavily on a sheet of tin while the polishing rolls will be adjusted to bear quite lightly upon the sheet of tin.

In operation a sheet of tin introduced in 40 the chute 16 will by gravity enter the rolls 6 and 7 and be fed between the polishing rolls 1 and 2. In passing the pipes 40 and 41 such dirt and foreign matter as may be comparatively loosely lying upon the sheet will 45 be disengaged by the blast of air and removed by the suction. The feed rolls 6 and 7 will feed the plate at relatively a slow rate of speed between the polishing rolls 1 and 2, which running at a relative high rate of 50 speed will remove any foreign matter from the surface and rub and polish the plate. As the last end of the sheet passes through the rolls 6 and 7, it will be quickly shot out of the rolls 1 and 2 without rubbing and polishing 55 the last portion to any material extent. The sheet will then be received on the chute 17 where it will be reversed end for end and introduced in feeding rolls 8 and 9. In passing through the rolls 8 and 9, the portion of 60 the sheet which was not sufficiently treated in the upper set of rolls will receive proper treatment in the first instance in these rolls, and the last end of the sheet will, of course, act the same as in the upper rolls and not be 65 materially polished by the lower set of rolls.

After passing the rolls 3 and 4 the sheet will be delivered into the chute 18 from whence it will be delivered on the carrier 19 by gravity. The position of the chute 17 may be adjusted by the screw 17^a to any desired angle ordinarily determined by the length and flexibility of the sheet. 70

In machines more or less of this character heretofore employed great trouble has been experienced with the feeding rolls in keeping them free from accumulation of dirt and from becoming solid and matted, and so as to inefficiently perform their duties. The blast of air provided in this machine acting 75 constantly on the rolls during their operation 80 serves well to remove any dirt or foreign substance from the rolls before it becomes embedded or matted therein, and the same in connection with the suction tube for removing the dirt and foreign matter, which 85 served particularly well to keep the surface of the rolls clean and soft and in suitable condition for their purpose, and maintain the rolls in true form whereby necessity for excessive pressure is obviated. 90

It is evident that numerous modifications and changes may be made in and from the construction herein shown and described without departing from the spirit of my invention and the subject matter of the claims. 95

What I claim as new and desire to secure by Letters Patent is:

1. The combination in a machine of the character described, having polishing rolls, of a blast pipe arranged adjacent to the roll 100 and provided with orifices to direct a blast tangentially on the rolls, and means for adjusting the said pipe with reference to the periphery of the roll, substantially as set forth.

2. The combination in a machine of the 105 character described, having polishing rolls, of a blast pipe arranged approximate to the roll and provided with orifices to direct a blast on the periphery of the roll, and a slotted suction pipe arranged adjacent to the blast pipe and adapted to receive and remove the dirt dislodged by the blast, substantially as set forth.

3. The combination in a machine of the character described, rolls, a blast pipe arranged adjacent to the periphery of the roll having orifices adapted to direct blast tangentially on the periphery of the roll, and a slotted receiving pipe arranged adjacent to the blast pipe and means for adjusting the 115 blast and receiving pipes towards and from the periphery of the roll, substantially as set forth.

In witness whereof, I have affixed my signature, in presence of two witnesses, this 5th 125 day of June 1907.

BRADFORD H. DIVINE.
